UNITED STATES PATENT OFFICE.

GEORGE L. LAMB, OF NAPPANEE, INDIANA.

SWEEPING-BRUSH.

SPECIFICATION forming part of Letters Patent No. 758,082, dated April 26, 1904.

Application filed January 14, 1904. Serial No. 189,049. (No model.)

To all whom it may concern:

Be it known that I, GEORGE L. LAMB, a citizen of the United States of America, and a resident of Nappanee, in the State of Indiana, have 5 invented a new and useful Improvement in Sweeping-Brushes, of which the following is a specification.

This invention relates to sweeping-brushes made up with tufts of "tampico" or like vegetable fiber. In brushes made of this fiber after they have been in use a while the tufts become so matted together that the brush becomes useless, especially if made of long fiber.

The leading object of the present invention 15 is to prevent such matting and to make a fiber brush as elastic as a bristle brush.

Other objects are to facilitate the construction of the improved brush and to provide for readily adjusting the spreaders to compensate 20 for wear, so as to prolong the life of the brush.

A sheet of drawings accompanies this specification as part thereof.

Figure 1 is a full length perspective view of the improved brush. Fig. 2 is a face view of 25 the head with some of the tufts removed to expose to view the parts inclosed by the fiber. Fig. 3 represents a cross-section on the line A B, Fig. 2. Fig. 4 is an end view of the brush-head with some of its tufts removed as 30 shown in Fig. 2, and Fig. 5 is a perspective view of one of the spreader-attaching devices hereinafter described.

Like reference numbers and letters refer to 35 like parts in all the figures.

The brush-head 1 is preferably and conveniently of an ordinary oblong form of wooden head, having tuft-sockets *a* in longitudinal rows, as shown at the ends in Fig. 2, and a central bolt-hole *b*, shown in the plane of section in Fig. 3. Either of the longitudinal 40 edges *c* and *d* of the head may be its front edge, both being preferably and conveniently parallel with said tuft-sockets *a*. The fiber 2 may be securely fastened in rows of tufts within said tuft-sockets *a* in any known or improved manner. The spreaders in pairs, 3 45 and 5 6, of stiff wire, having rebent ends, are loosely inserted between the rows of tufts and

are pivotally attached to the under side of the head 1 by a pair of pivoting and adjusting devices 7 and 8, one of which is segregated by Fig. 5. Each of these devices is fixedly held in place on the head by a wood-screw *e*. Each comprises an L-shaped angle-piece *f*, provided with the screw-hole and with a longitudinal slot 9, Figs. 4 and 5, in its perpendicular leg, a cross-bar *g*, having a pivotal hole 10, Fig. 5, for each spreader and a central hole, and a bolt or screw *h*, occupying said central hole and extending through said slot 9 in the perpendicular leg of the device. By loosening, moving, and retightening said screw *h*, and therewith said cross-bar *g*, each end of the spreaders 3, 4, 5, and 6 as a whole may be moved toward the head 1 to compensate for 55 the wear of the fiber 2 and restored to effective condition. The spreading of the fiber 2, which is the main object of the invention, is primarily effected by springs 11, 12, 13, and 14, reacting against the spreaders 3, 4, 5, and 6. In the form shown each spring reacts 60 against a pair of spreaders to which it is self-attached, being U-shaped, with suitably-hooked ends, as shown in Fig. 3.

The handle 15, Fig. 1, is preferably attached at a suitable angle to one of the longitudinal edges *c* or *d* of the head 1 by means of a socket-piece 16, having a steadyng-lip *i* to engage with such edge of the head, a central bolt 17 extending upwardly through said 75 bolt-hole *b* of the head and through a super-adjacent portion of said socket-piece, and a thumb-nut 18 on said bolt. By loosening and reversing said socket-piece 16, as represented by dotted outlines in Fig. 3, the opposite edge 80 of the head may be changed to its front, and any uneven wear of the fiber 2 may thus be corrected.

The number of spreaders will obviously depend on the number of the rows of the fiber-tufts, which is variable in brushes of different makes. The form, number, and arrangement of the springs may be changed without materially departing from the construction above described. The fiber may be 85 otherwise attached in rows, and other like 90

95

modifications will suggest themselves to those skilled in the art.

Having thus described said improvement, I claim as my invention and desire to patent 5 under this specification—

1. A fiber sweeping-brush provided with fiber-spreading springs, substantially as hereinbefore specified.

2. A fiber sweeping-brush having rows of 10 the fiber separated by spring-pressed spreaders to spread the fiber, substantially as hereinbefore specified.

3. A fiber sweeping-brush having rows of 15 the fiber separated by spring-pressed spreaders in pairs and springs reacting against said spreaders to spread the fiber, substantially as hereinbefore specified.

4. A fiber sweeping-brush having rows of 20 the fiber separated by spring-pressed spreaders in pairs and self-attached U-shaped springs reacting against said spreaders to spread the fiber, substantially as hereinbefore specified.

5. A fiber sweeping-brush having a head 25 provided with rows of the fiber, loose spreaders between the rows, means for pivotally attaching said spreaders to said head, and springs reacting against said spreaders to

spread the fiber, substantially as hereinbefore specified.

6. A fiber sweeping-brush having a head 30 provided with rows of the fiber, loose spreaders between the rows, means for pivotally attaching said spreaders to said head, means for adjusting the spreaders toward the head to compensate for the wear of the fiber, and 35 springs reacting against said spreaders to spread the fiber, substantially as hereinbefore specified.

7. The combination, in a sweeping-brush, of a head provided with fiber in rows, spreaders between such rows of the fiber, springs reacting against said spreaders to spread the fiber, and a pair of pivoting and adjusting devices each comprising an L-shaped piece fixedly attached to the head and having a longitudinal slot in its perpendicular portion, a cross-bar provided with pivot-holes for the respective spreaders, and a central screw extending through said slot and said cross-bar, substantially as hereinbefore specified.
